[57] CLAIM

The ornamental design for a paint cup assembly, sub-
stantially as shown and described.

DESCRIPTION

FIG. 1 is a right side elevational view of a paint cup
assembly showing my new design;

FIG. 2 is a left side elevational view thereof;

FIG. 3 is a front elevational view thereof;

FIG. 4 is a rear elevational view thereof;

FIG. 5 is a top plan view thereof, the upward extending
tubing omitted for convenience of illustration; and

FIG. 6 is a bottom plan view thereof.

The broken line representation of a spray gun in FIG. 2
is for purposes of illustration only.

FIG. 1

FIG. 2

FIG. 3

FIG. 4

FIG. 5

FIG. 6
